DESIGN FOR A COMBINED DIAL AND HAND FOR A CLOCK OR SIMILAR ARTICLE

Richard H. Bourne, El Reno, Okla.

Application February 13, 1939, Serial No. 82,947

Term of patent 14 years

To all whom it may concern:

Be it known that I, Richard H. Bourne, a citizen of the United States, residing at El Reno, in the county of Canadian and State of Oklahoma, have invented a new, original, and ornamental Design for a Combined Dial and Hand for a Clock or Similar Article, of which the following is a specification, reference being had to the accompanying drawing, forming part thereof.

Figure 1 is a plan view of a combined dial and hand for a clock or similar article showing my new design; and

Figure 2 is an edge view of the same.

I claim:

The ornamental design for a combined dial and hand for a clock or similar article, substantially as shown.

RICHARD H. BOURNE.
